Inventor:
Wm. M. Brooks
By L. Eastman, Atty.

UNITED STATES PATENT OFFICE.

WINFRED MUDGE BROOKS, OF EAST ORANGE, NEW JERSEY, ASSIGNOR TO E. J. BROOKS
& CO., OF NEW YORK, N. Y., A CORPORATION OF NEW YORK.

BOX-STRAP SEAL.

1,271,129.

Specification of Letters Patent.

Patented July 2, 1918.

Application filed March 22, 1918. Serial No. 223,922.

To all whom it may concern:

Be it known that I, WINFRED MUDGE BROOKS, a citizen of the United States of America, and a resident of East Orange, in the State of New Jersey, have invented certain new and useful Improvements in Box-Strap Seals, of which the following is a specification.

The object of this invention is to provide a simple, economical and efficient seal for metal box straps, capable of resisting heavy tension on said straps.

The invention consists in a novel mode of interlocking portions of the box strap itself in connection with the novel auxiliary seal part, hereinafter more particularly described.

One sheet of drawings accompanies this specification as part thereof, in which like reference characters denote like parts.

Referring to the drawings, Figure 1 represents a box secured by two box straps sealed in accordance with the present invention. Figs. 2, 3 and 4 show back, face and end views respectively of one type of the improved auxiliary seal part, unsealed; Fig. 5 shows a back view of this type sealed. Figs. 6, 7 and 8 show back, face and end views respectively of a modified type of the improved auxiliary seal part, unsealed; Fig. 9 shows a back view of this modified type sealed. Fig. 10 shows an enlarged cross-sectional view taken on the line $m-m$ of Fig. 5.

The improved auxiliary seal part is preferably constructed of substantially rigid sheet metal, and comprises a flat body portion a having two parallel sides turned down and under b forming substantially a sleeve adapted to receive two thicknesses of metal box strap. Each of said parallel sides b has two slits d extending into the depth of said parts b as shown in Figs. 2 and 6. These slits d may be said to define a waist part c (Fig. 2) or c' (Fig. 6) embraced between them. The box straps in the drawings are indicated by e .

In operation, the ends of the box strap are threaded from opposite ends through the auxiliary seal part a so that they lie one upon the other, their lateral edges embraced by the side and bottom portions b of the seal part. When the box strap has been drawn sufficiently tight by some suitable tightening device, the waist part c

(Fig. 2) or c' (Fig. 6) is constricted by being pressed downward and under by a suitable tool, shearing the portions of box strap embraced thereby along the lines of the slits d and folding said portions over within 60 said waist of the auxiliary seal part as shown in Fig. 10.

The only difference between the types of seal part illustrated by Figs. 2 and 6 lies in the waist parts c and c' , the former it will 65 be noted being adapted to meet after the sealing operation as shown in Fig. 5, while the latter is shortened and does not meet as shown in Fig. 9.

The sealed joint produced by this process 70 of sealing in conjunction with this novel seal part, provides positive shoulders made by the slits d to withstand longitudinal tension of the box strap, as is well shown in Fig. 10.

A plurality of waist parts may be provided where desirable and the depth of the slits and the corresponding extent of the construction of the waist part or parts may be modified to suit particular uses. Other 80 modifications will suggest themselves to those skilled in the art, within the scope of the present invention.

Having thus fully described my invention, I claim:

1. A mode of securing metal box straps, consisting of overlapping the ends of the box strap through an auxiliary metal sleeve adapted to embrace a portion of their edges and shearing, turning down and under portions of their edges thus embraced in conjunction with the corresponding parts of the edges of said auxiliary sleeve part, substantially as specified.

2. An improved seal member for sealing 95 metal box straps, consisting of a flat body portion having two parallel sides turned down and under to form a sleeve adapted to receive the overlapped ends of a box strap and having two slits extending in from each 100 side perpendicular thereto through and to the depth of the said under-turned or bottom parts of the sleeve.

3. An improved seal member for sealing box straps consisting of a sleeve of substantially rigid metal having a flat body portion, two parallel sides bent therefrom down and under to receive and embrace the edges of the overlapped ends of a box strap, 105 said sleeve having a waist part defined by 110

two slits extending in from each of said parallel sides, said waist part being adapted to being constricted by the pressing down and under of the parts between said slits on each side, such constriction operating to shear and turn down and under with said parts of the portions of box straps embraced thereby.

4. An improved metallic seal part for box straps adapted to admit the ends of a box strap endwise and to embrace their lateral

edges, such seal part being formed by parallel rectangular bends and having slits extending in from its sides defining a waist part adapted to be constricted, interlocking therewith the embraced portions of the box 15 straps, substantially as specified.

WINFRED MUDGE BROOKS.
